DESIGN FOR A CASH REGISTER

Walter Dorwin Teague and Walter Dorwin Teague, Jr., New York, N. Y., and Edward W. Herman, Dayton, Ohio, assignors to The National Cash Register Company, Dayton, Ohio, a corporation of Maryland

Application December 16, 1938, Serial No. 81,818

Term of patent 14 years

To all whom it may concern:

Be it known that we, Walter Dorwin Teague, Walter Dorwin Teague, Jr., and Edward W. Herman, all citizens of the United States, residing respectively at New York city, in the county of New York and State of New York; at New York city, in the county of New York and State of New York; and at Dayton, in the county of Montgomery and State of Ohio, have invented a new, original, and ornamental Design for Cash Registers, of which the following is a specification, reference being had to the accompanying drawings, forming a part thereof, in which—

Fig. 1 is a perspective view showing the front, right side, and top of the cash register.

Fig. 2 is a perspective view showing the back, left side, and top of the cash register.

Fig. 3 is a side elevation of the cash register.

We claim:

The ornamental design for a cash register, as shown.

WALTER DORWIN TEAGUE.
WALTER DORWIN TEAGUE, JR.
EDWARD W. HERMAN.
